UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR CONSTRUCTION.

1,293,207.

Specification of Letters Patent.

Patented Feb. 4, 1919.

Original application filed August 6, 1915, Serial No. 43,924. Divided and this application filed December 23, 1915, Serial No. 68,312. Renewed June 27, 1918. Serial No. 242,311.

To all whom it may concern:

Be it known that I, THOMAS NATHAN KUSSELL, a citizen of the United States, and a resident of Chicago, in the county of Cook and State of Illinois, have invented certain new and useful Improvements in Car Construction, of which the following is a specification.

This invention relates to car construction, particularly the construction of car frames, and has particular reference to the means employed for connecting together the structural elements of car frames.

The principal objects of my present invention are to provide improved means for connecting the ridge pole and purlins to the carlines, and particularly the end carlines; to provide improved means for connecting together wooden and metallic frame members; to provide improved means for supporting the end of the roof; and generally, to improve, cheapen and simplify the construction of car frames, and particularly the roof frame of cars.

In attaining these and other objects and advantages to be hereinafter pointed out, I have provided a construction one embodiment of which is illustrated in the accompanying drawings, in which:—

30 Figure 1 is a longitudinal, vertical, central section through the upper part of the end of a car constructed in accordance with my present invention;

35 Fig. 2 is a perspective view of the bracket or shoe provided for connecting the ridge pole and purlins to the end carlines; and

Fig. 3 is a perspective view of a modified form of bracket for use with the carlines intermediate the end carlines.

40 In the form of construction shown in the drawings the end carline 13 is of Z-shaped section, the lower flange 40 of which is connected to the Z-shaped end posts 12 by means of angle pieces 14. The upper flange

45 39 of the carline 13 is connected to the wooden ridge pole 15 by means of the bolt 17. Movement of the ridge pole relatively to the carline is prevented, not only by the bolt 17 which passes through the upper

50 flange of the carline, the ridge pole and the central roofing strip 30, but also by means of a shoe or bracket 18.

The section shown in Fig. 1 is taken through the ridge pole of the car so that

the central roofing strip 30, to which the 55 wooden roof is attached, is shown, as are also the transverse members 32 and 48 which carry the running board 33. The outer end of the running board is supported from the end plate 23 by means of a bracket 33. It 60 will be observed that the outer end of the roof through the roofing strip and ridge pole is firmly supported by the outer part of the bracket or shoe 18. By this construction the strain on the end plate 23 is relieved and 65 this is important as there is more strain on this portion of the roof than any other owing to the fact that it is the part on which the brakeman steps when passing from the ladder to the running board or to operate 70 the brake wheel.

The shoe or bracket 18 is formed with two vertical side portions 19 adapted to engage the two sides of the ridge pole or purlin and prevent lateral movement thereof. These 75 side portions are provided with laterally projecting horizontal wings 20 riveted or otherwise secured to the upper flange 39 of the carline. These laterally projecting wings make it unnecessary to provide a web on the 80 shoe which would lie between the flange 39 of the carline and the lower surface of the ridge-pole or purlin. Consequently, the ridge pole or purlins rest on the upper surface of the carline, as distinguished from a 85 surface depressed below the surface of the other portions of the carline. The two side portions 19 are connected at the end by the vertical portion 21 adapted to engage the end of the ridge pole or purlin and prevent 90 longitudinal movement of these parts relatively to the carline. Vertical flanges or webs 42 are provided to support the projecting portion of the shoe or bracket 18. The projecting parts of the side portions 19 are 95 connected by a horizontal portion 43 whose upper surface is flush with the upper surface of the flange 39 of the carline. By means of this construction a horizontal bearing or supporting surface for the ridge pole 100 or purlin is obtained whose length is considerably greater than the width of the upper flange of the carline. This is particularly important where the upper flange 39 of the carline decreases in width progressively from the sides of the car toward the center so that adjacent the running board the flange is particularly narrow in width. In

addition large lateral bearing surfaces are provided on either side of the purlin for preventing sidewise movement and relieving the bolt 17 from such function, which is important as the bolt has a comparatively small bearing surface on the wood of the ridge pole or purlin. Not only are the bearing surfaces increased, but also the construction of the upper end of the car is strengthened by the fact that the end plate 23 can be clamped directly by the bolt 49 against the vertical end portion 21 of the shoe 18 and is thereby more securely held in position than would be the case if it were secured to the end of the ridge pole or purlin.

Fig. 3 shows a modified form of shoe 44 for use in connecting the carlines intermediate the end carlines to the ridge pole or purlins. Its construction is similar to that of the shoe 18 except that there is no end portion equivalent to the part 21. The other parts, namely, the vertical portions 19^a, the laterally extending wing 20^a, the depending flange 22^a, the vertical flanges 42^a and the horizontal portion 43^a act in analogous manner to the parts 19, 20, 22, 42 and 43 of the shoe 18.

Having thus described my invention and illustrated its use, what I claim as new and desire to secure by Letters Patent is:—

1. A car construction comprising, in combination, a longitudinal roof member, an end plate, a Z-shaped end carline having an inwardly directed upper flange, an outwardly projecting lower flange and a substantially vertical central web, a shoe for connecting said longitudinal roof member to said carline attached to said upper flange and projecting over the lower flange of the carline with its outer end in contact with said end plate.

2. A car construction comprising, in combination, a longitudinal member, a carline having a substantially flat upper surface, and a surface downwardly directed therefrom, a bracket attached to said last-mentioned surface having an upper surface substantially flush with the upper surface of said carline, portions on said bracket adapted to engage the sides of the longitudinal member and the upper surface of the carline, means for attaching said portions to the carline, and means for attaching said longitudinal member to said carline and said bracket.

3. A car construction comprising, in com-

bination, a longitudinal wooden roof member, a Z-shaped carline having its central web vertically arranged, a bracket engaging said central web on the side opposite the upper flange and extending over the lower flange of the carline, the upper surface of the said bracket being substantially flush with the upper surface of said upper flange and in contact with the lower face of said roof member, and an upwardly projecting portion on said bracket adapted to engage the end of said roof member.

4. A car construction comprising, in combination, two roof members substantially at right angles to each other superimposed on each other, and a shoe mounted on the lower member comprising a portion projecting laterally from the side of said lower member having an upper surface substantially flush with the upper surface of said last-mentioned member, and portions adapted to engage the sides of the upper member and the upper surface of the lower member, and means for attaching said portions to said lower member.

5. A car construction comprising, in combination, an end carline, a wooden purlin resting on the upper surface of said carline, a shoe on said carline adapted to contact with a vertical face of said carline and with the undersurface of said purlin adjacent said vertical face of said carline, and also with the sides and end of the purlin.

6. In a car roof construction, in combination with a carline and a wooden purlin, a socket member adapted to maintain said carline and purlin in predetermined position having a flat surface adapted to abut laterally against the carline, a socket having side and end portions separate from said first-mentioned member and adapted to restrain the purlin from lateral and longitudinal movement relatively to the carline, and means for securing the abutting surface of said socket member and said carline together whereby they may be restrained from relative distortion.

In testimony whereof I have hereunto signed my name in the presence of the two subscribing witnesses.

THOMAS NATHAN RUSSELL.
